UNITED STATES PATENT OFFICE.

JOHN C. WHITRIDGE, OF COLUMBUS, OHIO, ASSIGNOR TO THE BUCKEYE STEEL CASTINGS COMPANY, OF COLUMBUS, OHIO.

CAR COUPLING.

Application filed December 29, 1926. Serial No. 157,724.

This invention relates to the buffer elements of automatic car couplings and has for its objects the provision of a structure which will furnish a buffing surface of greater area than has been heretofore attained and also reinforce either the guard arm or the knuckle side of the head or both sides of the head of the coupler. The invention is illustrated in the accompanying drawings and will be hereinafter fully set forth and particularly defined.

In the drawings, Figure 1 is a top plan view of a car coupling showing one embodiment of the invention,

Figure 2 is a side elevation of the coupling head with the buffer or strike plate in section,

Figure 3 is a bottom plan view,

Figures 4, 5 and 6 are views corresponding to Figs. 1, 2 and 3, respectively, but showing another form of the invention.

Referring more specifically to the drawings, 1 designates the head of an automatic coupling, and 2 designates a portion of the draft rigging in which the shank 3 of the coupling is mounted in the usual manner. The draft rigging carries a striking plate 4 which may be mounted in any approved manner but preferably has its front formed on a simple curve whereby it presents a convex surface 5 from end to end. The coupler head is formed with the usual buffing surface, as 6, on the rear wall of the lock housing.

According to the present invention, ribs 7 are formed on the exterior of the guard arm side and the knuckle side of the coupling head, and these ribs, at their rear ends, merge into laterally extending buffing shoulders 8 at the sides of the shank 3 of the coupling,

40 said shoulders presenting concave surfaces to the convex surface of the striking plate 4. The ribs 7 extend generally longitudinally of the coupling head but converge slightly rearwardly and the striking shoulders 8 are slightly in the rear of the striking surface 6, and it will be noted that the ribs not only sustain the striking shoulders 8 but also reinforce the guard arm and the knuckle housing so as to resist deformation and fracture thereof. The invention also provides a broad rib or reenforcing plate 9 on the bottom of the coupling head at the center thereof which terminates in a striking surface 10.

It will be observed that the area covered vertically by the ribs 7 is that included with-

in the usual lines of the head so that the form of the invention which has been described may be said to retain the general standard of the automatic coupler. In the form shown in Figures 4, 5 and 6, the central rib 71 corresponds in all respects to the central rib 7 of Fig. 2 but the upper rib 72 and the lower rib 73 increase in their vertical dimension rearwardly so that the striking shoulders 80 extend upwardly to the level of the top of the lock housing 81 and downwardly to the plane of the bottom of the rib or reenforcing plate 100, the striking area of said housing and said rib or plate being extended laterally to merge into the shoulders 80, as shown clearly in Figs. 4 and 6, so that there is a continuous uninterrupted striking surface the full width of the structure.

Heretofore, the rear wall of the lock housing was the only buffing surface on the head and the striking casting, consequently, received buffing forces only at a point above the level of the coupler shank. The buffing surfaces of the coupler and the striking casting were parallel with each other and at right angles to the longitudinal axis of the car. It has also been the practice to arrange draft stops and gear travel on new cars so that, under conditions of buff with maximum gear travel, there would be a small amount of clearance between the rear of the lock housing and the front of the striking casting. In service, due to wear and unavoidable deformation of the draft elements this clearance margin is gradually eliminated with the result that a certain portion of the buffing forces are dissipated through a blow of the coupler horn or lock housing against the striking casting.

In switching cars on tangent tracks with the coupler in a central position and the knuckles open, the side walls of the lock housing which transmit the buffing forces to the striking casting are able to perform this duty without undue damage to the front wall of the coupler. However, local deformation of the striking casting, due to the blow being concentrated on a small central area of the casting often results in fracture of the latter. It often happens that cars are switched together with the couplings out of center and with the knuckle closed in one or the other car. In this event, the force of the impact is delivered at the extreme point of the guard arm, and when the impact is greater than

the capacity of the draft gear, the guard arm of the coupling with the open knuckle and the knuckle side of the other coupling are frequently damaged to the extent of a cracked 5 front wall, and a broken guard arm may result. My present invention overcomes all these difficulties and avoids the described damages.

Having fully described my invention what 10 I claim as new and desire to secure by Letters-Patent, is:—

1. The combination with a striking plate, of the coupling head of an automatic car coupling provided on its lateral sides respectively 15 with laterally projecting longitudinally extending ribs terminating at their rear ends in lateral vertically extending buffing shoulders cooperable with said striking plate.
2. In buffing means for car couplings, the 20 combination with a striking plate, of an automatic coupling head provided at its rear end on its lateral sides with lateral buffer shoulders cooperable with said striking plate, vertically spaced laterally projecting ribs on the 25 coupling head at respective sides of the rear portion thereof and projecting respectively in opposite directions from said head, said ribs being disposed between the body of the cou-

pling head and said shoulders and reinforcing the latter, a lock housing rising from the coupling head and providing a vertical buffing face between said buffer shoulders cooperable with said striking-plate, and a member on the bottom of the coupling head affording a buffing face between said buffer shoulders cooperable with said striking plate.

3. In buffing means for car couplings, the combination with a striking plate, of the coupling head of an automatic coupling provided with a lateral vertical buffer shoulder at its rear end at each lateral side of the coupler shank cooperable with said striking plate, a lock housing rising from the coupling head and affording a buffer face between said shoulders cooperable with said striking plate, the upper end of the vertical shoulder being on a plane with the top of the lock housing and merged with the rear wall of said housing, and vertically spaced ribs on the lateral sides of the head and converging rearwardly 45 to merge into and reinforce the respective buffer shoulders.

In testimony whereof, I have signed this specification.

JOHN C. WHITRIDGE.
